UNITED STATES PATENT OFFICE.

FRANK RUSSELL GLASENER, OF CEDAR FALLS, IOWA.

SHEAF-DELIVERING CONVEYER FOR SHOCKING MACHINES.

Application filed August 2, 1923. Serial No. 655,296.

To all whom it may concern:

Be it known that I, FRANK RUSSELL GLASENER, a citizen of the United States of America, and a resident of Cedar Falls, 5 Black Hawk County, Iowa, have invented certain new and useful Improvements in Sheaf-Delivering Conveyers for Shocking Machines, of which the following is a specification.

10 My invention relates to improvements in sheaf-delivering conveyers for shocking-machines, and the object of my improvement is to supply for a grain shocking-machine a conveying mechanism adapted to receive 15 bound bundles of grain from a harvester binder and elevate and deliver them into the basket or shaping receptacle of the shocking-machine, means being also provided to synchronize the movements of the conveyer 20 relatively to those of the operations of the shocking-machine, by intermittently interrupting the progressive travel thereof; and means being supplied on the conveyer for 25 ejecting bundles of grain carried thereon at a suitable location for discharging them into said basket or receptacle.

The above purposes have been successfully accomplished by the means and mechanisms which are hereinafter described and claimed, 30 and illustrated in the accompanying drawings, it being understood that changes in the precise embodiment of invention herein disclosed can be made within the scope of what is claimed, without departing from the 35 spirit of the invention.

In the drawings: Fig. 1 is an elevation of the endless conveyer of my invention as viewed from the location of a binder delivering thereupon but not shown. Fig. 2 40 is a rear elevation of the conveyer and of the cooperating actuating mechanism therefor. Fig. 3 is a detail view, on a larger scale, of parts of said actuating mechanism. Figs. 4 and 5 are enlarged detail views of the 45 adjustable connecting means between the carrying and the sweep arms of the endless conveyer, showing them respectively in differently adjusted positions. Fig. 6 is a detail elevation of the internally dentated clutch element and pawl device, and Fig. 7 is an elevation of the cam-wheel and follower elements, with the said clutch element and pawl shown in dotted lines. Fig. 8 is an 50 edge elevation of the elements of said Fig. 7, omitting said follower elements.

In the above drawings, a harvester and

binder which deliver bundles of bound grain to the conveyer are not shown, nor a shocking-machine to receive and form shocks of bundles discharged into it by said conveyer. 60

The mechanisms shown are mounted for transportation upon carrying-wheels, as at 9, while the bed or way of the endless conveyer is connected rigidly by means of hitch members 58 and 59 to the frame of a harvester to be propelled therewith to and fro.

The bed or way comprises an imperforate sheet metal apron 1 set at an inclination upwardly from a transversely concaved bundle receiving part, the upper end of the apron 70 being directed horizontally to one side at 2, and thence downwardly obliquely at 3 abutting upon an upper edge of a basket or receptacle 4, such as that of a shocking-machine mounted movably on said carrying-wheels to the right. Mounted upon said apron 1 are a pair of spaced longitudinally directed tubular elements 5, adapted to receive thereon bundles of grain, the bundles being pushed therealong by the conveyer 75 carrying arms to the point of discharge, the tubes keeping the bundles spaced from the apron 1, diminishing friction and frictional wear of the apron.

Side-bars 63 are rigidly supported at opposite ends at front and rear of the apron 1 and have bearing-boxes thereon at 64 to receive the shafts 62 and 68, the shaft 62 carrying a sprocket-wheel 61 driven by a sprocket-chain 60 and sprocket-wheel 13. 90 Pairs of sprocket-wheels 65 and 66 are mounted on said shafts 62 and 68 at opposite parts of the apron 1 and carry the endless conveyer chains 67. Tubular elements 74 and 85, arranged in three pairs, are positioned in spaced relation transversely across the chains 67 and are secured to special links of the latter which have rigid standards 75 thereon directed at right angles thereto outwardly. 100

Referring to Figs. 4 and 5, the tubular elements 74 are rockingly mounted in sleeves which are fastened on said standards 75. For a purpose to be described, flat longitudinal bars 77 are secured by bolts 76 along said elements 74. Several carrying arms 73, preferably shaped from resilient rods, are terminally coiled about the elements 74, transversely spaced apart, and have the extremities of their coils inserted in and secured by holes in said bars 77, so that the arms normally are projected outwardly at 105 110

about right angles from the endless conveyer, having their free end parts slightly curved toward the direction of their travel with the conveyer.

5 The others of the pairs of elements shown at 85 are likewise mounted rockingly in sleeves secured on standards 75 at a distance of several chain links from the other element 74. The elements 74 and 85 are 10 connected by the following means. The numerals 79 and 80 denote connected sections of sectional links between the elements 74 and 85, being short bars twisted to have their abutting end parts in spaced 15 parallel relation, and clutch-disks 83 are secured respectively thereto on their opposite faces and have co-mating radially dentated faces, the disks being secured together as adjusted relatively by bolts 81 and the 20 nuts 82. The other end of each bar section 79 is shaped as a sleeve member 78 mounted loosely upon the element 74, while the outer end of the other bar section 80 is shaped into an elongated loop 84 in which 25 the element 85 is slidably mounted. It will be observed that the sectional linking means keep the two elements 74 and 85 at constant positional relation to each other, and that the clutch-disks permit angular 30 adjustments of the elements 74 and of the carrying arms 73, so that the angle of the arms may be varied as found necessary relative to the endless conveyer and according to the burdens to be moved or the proper 35 clearance thereof in use, and that the loops 84 afford the necessary shifting of the sections 80.

The elements 85 have transverse holes to receive the members or arms 86 of the 40 U-shaped rods 88, the arms 86 serving as sweeps for the carrying arms 73, and normally being positioned to cross the latter close to the elements 74, being kept yieldingly in this position by means of tension 45 springs 90 connected to the bars 77. The left-hand end of each tubular element 85 is bent into a crank 89 projecting inwardly relative to the conveyer. The numeral 69 denotes a cam-plate or tripping-device 50 which is rigidly mounted at the left-hand upper angle of the conveyer frame in the path of progressive movement of the crank 89 to trip or rock the latter together with the element 85 and the sweep arms 86 at 55 that location, whereby the arms 86 are caused to swing outwardly across and along the carrying arms 73 to discharge the burden carried on the latter arms, such as a bundle of bound grain, into the open top 60 basket or shaping receptacle 4 of the shocking machine. When the crank 89 has been carried forward by the conveyer far enough to clear said cam-plate 69, the reaction of the stretched spring 90 swings back the 65 sweep arms 86 to their initial positions.

Referring now to Figs. 2, 3, 6, 7 and 8, the carrying wheels are positioned at 9 to the right of the bed or way of said conveyer, one wheel 9 only being shown, and which supplies the driving power for operating 70 the conveyer as also for the moving parts of the shocking machine not shown. The wheel 9 referred to has its axle 10 rotatably mounted in bearing holes in the members of a U-shaped frame-bar 8, one end 75 of the axle carrying a sprocket-wheel 44 and the other end carrying a bevel-gear 11. The U-shaped member 8 is hung on hangers 7 and 19 having bracket-bars 41 and 57 which together with a standard 6 80 support the lower and upper ends of the bed or way of the conveyer.

A shaft 13 is mounted in a bearing suspended from the bracket-bar 57, and carries on its forward end a bevel-pinion 11 in mesh with said bevel-gear 12. The sprocket-wheel 16 is mounted loosely and longitudinally slidably on the rear part of the shaft 13 and has a hub clutch-face 15 dentated to mate with a dentated clutch-face on a sleeve 14 fastened on said shaft. A flanged collar 18 is riveted on the rear extremity of said shaft, and a coiled compression-spring 17 is mounted on the shaft engaged between the collar 18 and the sprocket-wheel 16. A sprocket-chain 60 connects the sprocket-wheels 61 and 16. Plates 30 and 31 are fastened on the hangers 19 and 7 respectively and have alined bearing orifices to seat the middle horizontal part of a rock-shaft 28 which has oppositely projecting crank parts 27 and 29 extending respectively downwardly and upwardly, the upper end of the crank 29 being bent over angularly and carrying a rotatable cam-roller or follower 32.

On the lower crank 27 is a loop 26 which receives and supports the upper looped part of a medially bent fork 21 whose lower terminal forks embrace the clutch-hub 15 of the sprocket-wheel 16 to bear against the adjacent face thereof, and opposing the action of the spring 17 at times. A coiled tension spring 20 is connected between said loop 26 and the hanger 19 and acts to tension the crank 27 rearwardly and keep the roller 32 on the upper crank 29 in bearing contact with the circumferential cam edge of a cam-wheel 33, the latter being loosely and non-slidably mounted on a fixed shaft 34 abutting a stop-collar 35, the shaft 34 with a stop-sleeve thereon being mounted in a boxing 36. On a bracket 37 is pivoted a bell-crank lever 38, an operating pull-chain 39 being connected to one member thereof, and a link 40 connecting the other member thereof to the crank 29.

A sprocket-wheel 42 is mounted loosely and non-slidably on the shaft 34 and has on one face an open end cylindrical clutch-

member or ring 54 having internal teeth 55. A pawl arm 52 is pivotally mounted on the cam-wheel 33 and has a roller 53 mounted rotatably on one face to at times engage between teeth 55 on the member 54. A tension spring 51 is connected between said arm 52 and a bolt 50 on the cam-wheel to normally retain the roller 53 engaged with said teeth 55.

10 The cam-wheel 33 has opposite cam edges at 48 and 49, concentric axially but with different radii and joined by a shoulder 47 on one side, and on the opposite side by a projection 45 with adjacent hollow and shoulder at 46.

15 The carrying wheel 9 drives the gearing 11-12, shaft 13 and sprocket-wheel 16, the latter being normally clutched to said shaft by tension of the spring 17, as the forks 21 are medially fulcrumed in bearing openings in a flange-plate 22 adjustably mounted on an angle-plate 25 with spacing washers 23 on connecting bolts 24. The sprocket-wheel 16 by means of the chain 60 drives the 25 sprocket-wheel 61 and shaft 62 to advance the endless conveyer. The pull-chain 39 may be used in order to rock the crank 27 oppositely to cause a rocking of the forks 21 oppositely to push the sprocket-wheel 16 30 out of clutch while compressing the spring 17.

20 The cam-wheel 33 is used to impart certain movements to the movable parts of the shocking-machine not shown, as the various projections and hollows of the cam edge act upon the follower roller 32 in pushing it outwardly or allowing it to return inwardly under the tension of the spring 20. This causes an intermittent connection and 25 disconnection of the sprocket-wheel 16 relative to the shaft 13, to effect intermittent action of the endless conveyer at times when related movements of the shocking-machine are made. The conveyer is thus automatically intermittently controlled as necessary in the operation of the shocking-machine, and in the proper delivering of bundles of grain to the latter in synchronizing the actuations of these mechanisms.

50 Having described my invention, what I claim as new, and desire to secure by Letters Patent, is:—

1. In combination, an endless conveyer, including rockingly adjustable cross-elements thereon and having outwardly projecting arms, other arms rockingly mounted on said conveyer and positioned normally to cross the plane of the first-mentioned arms, resilient means for yieldingly retaining the second-mentioned arms in said position, and means for releasably tripping the latter arms on arriving at a certain location to shift them relatively to the first-mentioned arms in engaging and ejecting a load carried by said arms.

2. In combination, an endless conveyer containing rockingly adjustable cross-elements having outwardly projecting arms, means for releasably securing said elements in adjusted positions, other arms rockingly mounted on said conveyer and positioned normally to cross the plane of the first-mentioned arms, resilient connections between said conveyer and said second-mentioned arms for yieldingly retaining them in said position, and means for releasably tripping the latter arms on arriving at a certain delivery position to sweep a loading off the first-mentioned arms.

3. In combination, an endless conveyer having outwardly projecting arms mounted thereon for pivoted adjustments, other arms mounted on said conveyer loosely, and a linking connecting means between the first- and second-mentioned arms longitudinal with the conveyer, said means containing adjustably comated elements detachably secured together to vary the angular position of the first-mentioned arms relatively to the conveyer.

4. In combination, an endless conveyer having outwardly projecting spring arms mounted thereon, other arms pivotally mounted on the conveyer in a following position, means for yieldingly elastically retaining said arms in a certain positional direction relative to the first-mentioned arms, means for releasably shifting the position of the second-mentioned arms relative to the first-mentioned arms to sweep the latter at a certain location in the path of travel of the conveyer, connecting means between the first- and second-mentioned arms for adjusting the angular position of the former, and mechanism for moving said conveyer in a certain direction, including disconnectible clutch elements.

5. In combination, an endless conveyer, a bed or way over which it is positioned inclinedly to project upwardly therebeyond adjustable rock-bodies on said conveyer, burden-receiving and carrying arms projecting from certain of said conveyer rock-bodies outwardly, sweep-arms mounted upon the other rock-bodies of said conveyer adjacent to the carrying arms to swing across the latter, interlocking connections between said sets of rock-bodies to permit of the rocking adjustment of the first-mentioned rock-bodies, and means positioned to engage and swing said sweep-arms across the carrying arms and at a location to eject the burden of the latter beyond the upper limit of said bed or way into a receptacle located to receive it.

6. In combination, an inclined bed or way, sprocket-wheels mounted thereon, sprocket-chains mounted on said wheels, sets of rockable connecting elements between the sprocket-chains, relatively fixed outwardly

projecting arms mounted on certain of said elements, arms mounted on other of said elements in front of the first mentioned elements relative to the direction of their travel,
5 an adjustably interlocked pair of members connected between the elements of each of said sets of elements with one member of each pair fixed to a first-mentioned element and the other member of the pair slidably
10 connected to a second-mentioned element, a cam-plate secured on said bed or way, the second-mentioned elements having a terminal crank and said cam-plate being positioned in the path of movement of the said
15 cranks to releasably swing them to shift the second-mentioned arms to sweep the first-mentioned arms, resilient means connected to the second-mentioned arms to return them when released by said cam-plate,
20 and mechanism for propelling said sprocket-wheels and chains in one direction.

7. In combination, an endless conveyer, mechanism for disconnectibly and intermittently propelling it in a certain direction, 25 means for manually controlling said mechanism, devices mounted on said conveyer for engaging and receiving burdens and carrying them to a position for unloading them, and other devices mounted movably on the
30 conveyer to sweep the first-mentioned devices successively on arriving at said unloading position to discharge the burden into a receptacle, and releasably and adjust-

ably interlocked members connected between said sets of devices for relative adjustments 35 of the first-mentioned devices relative to the conveyer.

8. In combination, a bed or way mounted for transportation, an endless conveyer mounted on said bed or way to project at its delivery end therebeyond, devices mounted adjustably on said conveyer for engaging and receiving burdens and carrying them to a position for discharging them into a receptacle, other devices movably mounted in 40 a following position to the rear of the first-mentioned devices to sweep the latter, and normally set at an angle thereto and across them, means for yieldingly and elastically retaining the latter devices in said position, a cam-plate mounted fixedly on said bed or way to be engaged by the sweep devices at a certain position to shift the latter across and along the carrying devices to eject their burdens, means for adjusting the angle of 45 position of the carrying devices relative to the conveyer, and mechanism disconnectibly connected to and adapted to operate said endless conveyer, said mechanism including a cam-wheel and follower roller for intermittently placing the mechanism in and out of operative relation to the conveyer.

Signed at Waterloo, Iowa, this 2nd day of July, 1923.

FRANK RUSSELL GLASENER.
